RETRACTABLE PEN DEVICE

Frank C. Wallace, North Hollywood, Calif.

Application January 10, 1949, Serial No. 70,011

8 Claims. (Cl. 120—42.03)

1

My present invention has to do with improvements in pens and has as its primary object the provision of a pen in which the writing element is automatically protracted and retracted by gravity in response to pointing the barrel either upwardly or downwardly.

Another object is to provide a protractable and retractable pen of this character in which the writing element is automatically locked in protracted position by gravity movement of a locking member.

Another object is to provide a protractable and retractable pen which is extremely simple and economical of construction.

A further object is to provide a pen of this character which is so constructed as positively to prevent leakage of ink into a pocket in which the pen is being carried, and therefore requires no separate cover or sealing element for the writing end of the barrel.

Other objects will appear hereinafter.

I shall now describe a presently preferred embodiment of my invention, for which purpose I shall refer to the accompanying drawing, wherein:

Fig. 1 is a longitudinal section showing the writing element in retracted position;

Fig. 2 is a longitudinal section showing the writing element locked in protracted position; and

Figs. 3 and 4 are sections taken on line 3—3 and 4—4, respectively, of Fig. 2.

The pen has a barrel 5 which may be made of metal or plastic, the barrel being comprised of a lower or inner end portion 5a and an upper or outer end portion 5b—that is, portion 5a is the lower portion and 5b is the upper portion, when the writing element is retracted, although when the writing element is protracted portion 5a becomes the upper portion and portion 5b becomes the lower portion. Said portions 5a, 5b are detachably secured together by means of sleeve-like insert 7 which is force fitted into the open end of portion 5b, the sleeve having a reduced diameter, externally threaded part 7a onto which the open end of portion 5a is threaded.

Barrel portion 5b has a pointed outer end, open at 9 to pass the outer pointed end 10 of a writing element such as a ball pen element 11. Such elements are of well known construction, comprising an ink tube 15 having a writing ball 16 mounted to freely rotate in its outer end.

Barrel portion 5a has a relatively thickened lower end portion 20 providing an outwardly facing annular shoulder 21, and a sleeve 25, 55

2

shaped to conform to the inner shape of the barrel, is frictionally fitted into barrel portion 5a, providing an annular shoulder 26 against which the lower end of the writing element engages. A split sleeve 24 resiliently engages the lower end of the tube, the sleeve having an enlarged portion 27 to which is secured, as by a screw 28, an L-shaped member 30 having a depending arm 30a laterally offset from the axis of the ink tube. The portion 27 is too large in diameter to pass the shoulder 26 into the reduced diameter portion 25a of the sleeve 25.

The inner portion 25a of the sleeve provides a cage slidably confining a weighted locking member 35. The locking member has a cylindrical portion 35a and a reduced diameter hemispherical end portion 35b, an annular shoulder 35c being provided at the intersection of portions 35a and 35b.

20 A carrying clip 40 is secured to the barrel portion 5b as by a rivet 41.

The device is shown in Fig. 1 in inverted or retracted position, which is the normal position in which the pen is carried in the pocket. In 25 that position writing element 11 drops into the barrel by gravity, its inward movement being arrested by the shoulder 26, and the locking member 35 normally rests against the flanged inner end 37 of the sleeve 25. It will be apparent and 30 that when the parts are in that position it is impossible for ink to leak from the pen unit into the pocket in which the pen is carried.

When it is desired to write with the pen, the barrel is reversed end for end from the position of Fig. 1 to that of Fig. 2, in which latter position the open end of the barrel is disposed downwardly. The writing element slides downwardly until the tapered portion of the pointed end of the writing element engages the inner periphery of the opening 9, in which position the ball 16 is exposed for writing purposes. Simultaneously 40 the locking member 35 slides by gravity in sleeve 25 until the arm 30a of element 30 becomes sandwiched between the inner surface of the sleeve and the outer surface of the hemispherical portion 35b, the outer end of the arm 30a abutting against the shoulder 35c. Thus, inward pressure on the writing element causes the writing element to bear at its inner end against the annular shoulder 26, preventing further inward movement of the writing element until the barrel is again inverted into the position of Fig. 1 or into such position that the parts will retract by gravity.

50 I find that it is desirable to slightly bevel the

shoulder 26 so that when the pen is again returned to the position of Fig. 1, the arm 30a will readily slide downwardly past the shoulder 26 to permit instant retraction. The hemispherical shape of the portion 35b of the locking member also facilitates this free retractive action since it does not tend to wedge the arm 30a against the inner surface of the sleeve.

It will also be apparent that a pen may be constructed very economically in accordance with my invention because it requires only a minimum of simple parts and assembly is greatly simplified.

I claim:

1. A pen device comprising a barrel open at its outer end, an elongated writing element mounted in the barrel to move axially by gravity through said open outer end, means limiting axial movement of the writing element relative to the barrel, said barrel having an interior outwardly facing shoulder between its ends, an arm carried by the inner end of the writing element, said arm being laterally offset from the axis of the writing element and projecting therefrom in a direction towards the inner end of the barrel, a weight member mounted in the inner end portion of the barrel to move axially thereof by gravity, said weight member having a reduced outer end portion engageable against the arm to urge the arm against the inner surface of the barrel at a point outwardly from the shoulder when the outer end of the barrel is pointed downwardly, and being disengageable therefrom in response to pointing the outer end of the barrel upwardly.

2. A pen device comprising a barrel open at its outer end, an elongated writing element mounted in the barrel to move axially by gravity through said open outer end, means limiting axial movement of the writing element relative to the barrel, said barrel having an interior outwardly facing shoulder between its ends, an arm carried by the inner end of the writing element, said arm being laterally offset from the axis of the writing element and projecting therefrom in a direction towards the inner end of the barrel, a weight member mounted in the inner end portion of the barrel to move axially thereof by gravity, said weight member having a hemispherical outer end portion engageable against the arm to urge the arm against the inner surface of the barrel at a point outwardly from the shoulder when the outer end of the barrel is pointed downwardly, and being disengageable therefrom in response to pointing the outer end of the barrel upwardly.

3. A pen device comprising a barrel open at its outer end, an elongated writing element mounted in the barrel to move axially by gravity through said open outer end, means limiting axial movement of the writing element relative to the barrel, said barrel having a bevelled interior outwardly facing shoulder between its ends, an arm carried by the inner end of the writing element, said arm being laterally offset from the axis of the writing element and projecting therefrom in a direction towards the inner end of the barrel, a weight member mounted in the inner end portion of the barrel to move axially thereof by gravity, said weight member having a reduced outer end portion engageable against the arm to urge the arm against the inner surface of the barrel at a point outwardly from the shoulder when the outer end of the barrel is pointed downwardly, and being disengageable therefrom in response to pointing the outer end of the barrel upwardly.

4. A pen device comprising a barrel open at

its outer end, an elongated writing element mounted in the barrel to move axially by gravity through said open outer end, means limiting axial movement of the writing element relative to the barrel, said barrel having a bevelled interior outwardly facing shoulder between its ends, an arm carried by the inner end of the writing element, said arm being laterally offset from the axis of the writing element and projecting therefrom in a direction towards the inner end of the barrel, a weight member mounted in the inner end portion of the barrel to move axially thereof by gravity, said weight member having a hemispherical outer end portion engageable against the arm to urge the arm against the inner surface of the barrel at a point outwardly from the shoulder when the outer end of the barrel is pointed downwardly, and being disengageable therefrom in response to pointing the outer end of the barrel upwardly.

5. A pen device comprising a barrel tapering towards and having an open outer end, a sleeve mounted in the barrel at a point spaced inwardly from its outer end, the sleeve having a reduced diameter portion providing an outwardly facing bevelled annular shoulder, a writing element having a tapered outer end portion and mounted to move by gravity axially in the barrel between a position in which its inner end engages said shoulder and a position in which its outer end engages the inner periphery of the opening in the outer end of the barrel, an arm carried by the inner end portion of the writing element, the arm being offset from the axis of the writing element and projecting therefrom in a direction towards the inner end of the barrel, a weight member mounted in the sleeve to move axially thereof by gravity, the weight member having a reduced upper end portion engageable against a side surface of the arm to urge the arm against the inner surface of the sleeve at a point outwardly from the shoulder when the outer end of the barrel is pointed downwardly and being movable by gravity out of said arm engaging position when the outer end of the barrel is pointed upwardly.

6. A pen device comprising a barrel tapering towards and having an open outer end, a sleeve mounted in the barrel at a point spaced inwardly from its outer end, the sleeve having a reduced diameter portion providing an outwardly facing bevelled annular shoulder, an ink tube having a tapered outer end carrying a writing ball, a sleeve fitting over the inner end of the tube, an arm carried by the latter sleeve, the arm being laterally offset from the axis of the tube and projecting from the sleeve in a direction towards the inner end of the barrel, and a cylindrical weight member mounted to move by gravity axially in the barrel toward and away from said annular shoulder, the weight member having a reduced diameter upper end portion engageable with a side surface of the arm to urge the arm against the inner surface of the first mentioned sleeve when the barrel is disposed with its outer end pointed downwardly, and when the inner end of said arm is against said annular shoulder.

7. A writing device comprising a barrel open at its outer end and presenting an interior outwardly facing annular shoulder, an elongated writing element having a writing implement on its outer end and an axially offset projection extending beyond its inner end, said element being mounted in the barrel to move axially thereof through the open end of the barrel, and gravity

movable means in the barrel operable when the barrel has its open end pointed downwardly to hold said projection against said shoulder, said means comprising a weighted spherical member mounted to move axially of the inner end portion of the barrel.

8. A gravity actuated, retractable point writing instrument comprising: a tubular cartridge for writing fluid, said cartridge being connected to a conical writing head carrying a freely rotatable ball; an outer barrel provided with a writing port and a cartridge chamber in communication therewith, the inner surfaces of the chamber adjacent the port being adapted to form a seat for the writing head when in writing position; a recess in the barrel opposite said writing port and adapted to selectively receive the end of the tubular cartridge; a shoulder between the recess and the chamber, said shoulder being spaced from and facing the writing port and engageable with the end of the cartridge when the writing head thereof is in writing position in the port;

and a weighted member slidably positioned in the recess, cooperating means on said member and said cartridge mutually engageable when said member is moved to the end of said recess nearest said shoulder, to cause the end of said cartridge to engage said shoulder, said cooperating means being completely disengaged when said member is moved in said recess away from said shoulder.
